UNITED STATES PATENT OFFICE.

JOHN DAY, GEORGE DAY, AND JENKIN JENKINS, OF MAESTEG, ENGLAND.

DIVING APPARATUS.

SPECIFICATION forming part of Letters Patent No. 521,208, dated June 12, 1894.

Application filed September 25, 1893. Serial No. 486,444. (No model.)

To all whom it may concern:

Be it known that we, JOHN DAY, GEORGE DAY, and JENKIN JENKINS, subjects of the Queen of England, residing at Maesteg, Wales, England, have invented certain new and useful Improvements in Diving Apparatus, of which the following is a specification.

This invention relates to diving apparatus whereby operations may be carried on at much greater depths than is possible with diving dresses and similar apparatus.

The invention will be best understood by reference to the accompanying drawings, in which—

15 Figure 1 is a section of a diving apparatus constructed according to this invention. Fig. 2 is a detailed view of the grappling apparatus showing the jaws in their closed position. Fig. 3 is a view of the grappling jaws open. 20 Fig. 4 is an inverted plan showing the under side of the ballast chamber and detachable ballast, and Fig. 5 is a section showing the preferred construction of ballast detent or fastenings. Figs. 2, 3 and 5 are drawn to a 25 larger scale than that to which Figs. 1 and 4 are drawn.

Like letters represent like parts throughout the drawings.

A represents a vessel of any suitable shape, 30 construction and material, preferably mild steel plates having a flat bottom or otherwise so shaped that if necessary it may take a firm hold upon the ground and provided with a ballast chamber B in which may be inserted 35 any suitable form of ballast or heavy material to sink the chamber. As it is very desirable for the occupants of the vessel to be able to disconnect the ballast in case of emergency or to facilitate the raising of the vessel A to the surface, the chamber B may be 40 provided with a door or doors operated from inside the vessel to allow the escape of the ballast when opened. Or several ballast chambers having doors controllable from inside the vessel may be placed about the vessel where required. Perhaps the most efficient plan would be to have one or more solid iron or lead blocks or plates secured by fastenings detachable from inside the vessel 45 as hereinafter described with reference to

Figs. 4 and 5; in the case of a single plate covering the whole bottom one or more holes may be formed in it so that it may not obstruct the bottom light or window.

In the arrangement shown in Fig. 4 the ballast consists of three heavy metal blocks viz.—a central block S and two outer blocks S'. The blocks S' when in their operative position, as shown in Figs. 4 and 5, are supported on their outer edges on bars or beads B' rigidly secured to or formed in part with the adjacent walls of the chamber B. In this construction of apparatus it is desirable to strengthen the floor of the diving chamber A for which purpose we prefer to rivet or otherwise secure to its under side say four angle-iron bars A² which extend completely across the floor. These bars are arranged at a suitable distance apart as shown and are provided with advantageously four ballast-securing devices, each of which, as shown in Fig. 5, consists of a T-shaped key T T' which may be supported at its lower end by means of a center point T² which rests in a suitable recess formed in a transverse bar or bridge-piece A³ connecting the two bars A² at the parts where these ballast-retaining devices are arranged. The upper part T of each key T T' is cylindrical except at its upper end T³ which projects into the interior of the chamber A where it is formed square or otherwise suitably adapted for being operated by a spanner or wrench. The part T of the key T T' is tightly packed in a stuffing-box U screwed or otherwise suitably secured in the floor A' and which in the usual manner is provided with a gland U'. The bars A² are provided with slots A⁴ to enable the ends of the part T' of the key T T' to project out through them and also to enable the said part T' to be turned inward so that its ends may be withdrawn from the outside of the bars A² and moved into the space between the two said bars A². The adjacent edges of the weights S S' are provided with recesses S² and S³ the former to allow them to fit over the angle-iron bars A² and the latter to admit of the parts T' of the keys T T' engaging with them in the manner shown clearly in Fig. 5.

It will be readily understood that when the

keys TT' occupy the positions shown in Figs. 4 and 5 in relation to the weights S S' said weights are rigidly secured in position and that when the keys T T' are turned so that 5 the outer ends of the parts T' thereof become disengaged from the recesses S³ the weights S S' will readily fall out of the chamber B.

If desired the keys T T' may be connected together so that at one operation they may all 10 be simultaneously released; or they may be connected and operated in pairs.

Eye-bolts or equivalent may be provided on the blocks S S' so that should they have 15 previously been detached from the diving apparatus, they may, at a subsequent descent of said diving apparatus, be readily attached to a cable, chain or equivalent by which to raise them to the surface.

The interior of the vessel A may be supplied with air by a pipe C which may be carried down inside the chamber if desired or the opening may be made lower down than is shown in Fig. 1; the vitiated air may be withdrawn from the chamber by the pipe D 20 both pipes being connected with suitable pumping apparatus upon the vessel conducting the diving operations. These pipes should be flexibly and suitably connected to the vessel and must be so supported or in 25 themselves sufficiently strong to stand, without collapsing, the pressures to which they may be subjected, so that the pressure inside the vessel A need not exceed something like 30 seventeen pounds on the square inch no matter what the pressure outside may be. Each 35 of these pipes may be fitted with a suitable valve or cock—automatic if desired—and controlled from inside the vessel for the purpose of regulating the air supply or closing the 40 entrance or exit in case of breakage of the tubes or other emergency. The chamber is lowered by any suitable rope or chain E suitably jointed as at E' to the vessel A. The chamber is also supplied with any convenient 45 arrangement of door or doors by which access may be had to the interior, the men working this apparatus being inside it so that the vessel must be sufficiently large to accommodate the men and allow room for their 50 movements.

The vessel A is provided at any convenient part with any desired number of windows F through which the occupants of the vessel can see the outside surroundings and has also 55 suitable electric or other search light apparatus G by which light may be thrown upon the surrounding objects. The light apparatus G may be arranged either inside or outside the vessel but preferably inside and if 60 electric light be used the wires for supplying the current may be carried through one of the air pipes or a special conductor may be provided in connection with the cable E. The light apparatus should be so arranged that it 65 can be turned where required and there

should either be more than one of these apparatus or it should be capable of being moved from one part of the vessel to another so as to throw the light wherever required. There should be at least one window in the bottom 70 or reflectors to enable the occupants to see below them; a search light must also be in the bottom or so arranged with reflectors or otherwise as to be capable of casting their light beneath the vessel. 75

The vessel is provided with any suitable number of grapplers H passing through ball-and-socket joints in the wall of the vessel so that by moving the grappler inside the vessel the outside jaws may be worked as required. The construction of the grappler may be as follows, and will be best understood by reference to Figs. 2 and 3 of the drawings. The ball-and-socket joint consists of a suitable socket I preferably formed in 80 two parts with packing J between them the outer half being bolted to the wall of the vessel A by the double ended bolts K while the inner half of the socket I is bolted to the first half by the same bolts K each of which is 85 screwed and carries a nut at each end as is clearly shown in Fig. 2. By this means the outer half of the socket is firmly bolted to the wall of the chamber while the inner half is forced tightly upon the packing J thus making a tight joint. The ball L fits closely in 90 the socket I and with the assistance of the packing J which by the pressure it sustains is forced tightly upon the ball, makes a tight joint of the socket. The ball L is hollowed 95 and formed into a stuffing box with a gland L' the end of which may be hexagonal so that it may be screwed up with a spanner and thus make a water-tight joint around the tube H which forms the body of the grappler. 100

I' is a winged bolt which may be screwed tightly against or slightly into the ball L whenever it may be desired to screw or unscrew the gland L', so as to hold the ball L and gland firmly in position during such adjustment. At its end, outside the vessel, the tube H is screwed or otherwise securely fastened to the socket H' or the latter may be integral with H which carries the pivoted grappling jaws M each of which is provided 115 with a projecting lug M' adapted to engage with an annular groove N² formed in the head N' of the rod N which passes through the grappler body H and at its inner end N³ is threaded for the reception of the nut O which 120 may be turned by handles O'; the end N³ preferably may have a collar N⁴ secured upon it to prevent the rod N from being forced too far outward.

Upon the inner end of the grappler body 125 H are handles H² which as shown in Fig. 2 may with advantage be screwed upon H and locked thereon by the long nut P also screwed on to the inner end of H and leaving a hollow space or stuffing box P' in which suitable 130

packing may be placed so as to make a water-tight joint around the rod N. A hexagonal collar P² may be formed upon the nut P which is reduced and extended at P³ where a collar 5 or ring Q is fixed upon it by screws Q' or other suitable means. The boss or nut of the handles O' is recessed so as to fit over the collar Q and is then connected by screws R' or other suitable means with a collar R which may be 10 placed upon the extension P³ before the collar Q is fixed. By this means the nut O when turned by the handles O' will turn round upon the nut P so as to force the rod N inward or outward as required. When the rod is pulled 15 inward as far as it will go the jaws M will be closed as shown in Fig. 2 by reason of the head N' acting upon the lugs M' of the jaws; when the rod N is forced outward to its extreme limit the jaws M are wide open as shown 20 in Fig. 3. To prevent the rod N from turning round independently of the grappler body H any convenient device may be employed such as a feather upon the rod working in the nut P or the head N' being arranged so as to 25 engage with one or both of the jaws M.

The operation of the grappler is as follows:—By the handles H² the tube H can be pulled in or out or turned round its axis as required while by the ball-and-socket joint 30 the handles can be caused to describe a circle or any other required figure so that the jaws can be moved about in any required direction in order to engage with the object outside the vessel A which it is required to grasp. This 35 object would generally be a chain, cable or the like to be secured to the sunken vessel or other object to be raised, the vessel A not being intended to receive objects from the outside when beneath the water but merely to enable 40 the divers to reach objects at great depths below the surface and to secure cables or the like to them by which the objects may afterward be raised. As already explained the jaws M can be opened or closed by means of 45 the handles O' as required, and a firm grip of the jaws can be secured by applying sufficient pressure to the handles O'.

Several grapplers H may be placed at suitable intervals around the vessel and if desired at different heights; if the vessel be a large one the grapplers can either be of considerable length or in a smaller vessel they may be of reduced length and will then not interfere with each other. Or again, while 50 one grappler is in use the others may be forced outward to their greatest extent so as not to be in the way. Or again, the grapplers which are not required may when the apparatus is above water be removed from 55 their sockets and the holes plugged up and made water-tight by means of the gland L'. Communication may be established with the attendant vessel by any convenient means preferably by telephone.

65 Instead of the grappling jaws described the

grappler or the body H thereof may be fitted on its outer end with any suitable form of grips, shears, drills, hooks, or other apparatus required any of which may be operated by suitable mechanism from inside the vessel. 70 Thus shears may be operated substantially in the same manner as the grappler jaws; drills may be operated by connecting them to the spindle N and revolving that by any suitable apparatus inside the chamber. Other 75 apparatus may be operated in the manner found most convenient.

Although the vessel A B in Fig. 4 is shown to be of rectangular form in horizontal section it will readily be understood that it may 80 be cylindrical or of other form.

We claim—

1. In a diving apparatus, such as described, the combination with the hermetically closed vessel having the ballast chamber, in the bottom provided with fixed projections, of ballast blocks having one edge supported on said projections and a movable key upon which the opposite edges rest, said key passing through to the inside of the vessel, whereby 90 said blocks may be released by the diver within the vessel; substantially as described.

2. In a diving apparatus, such as described, the combination with the hermetically closed vessel having the ballast chamber in the bottom provided with fixed projections and the angle irons slotted transversely, secured beneath the bottom of the vessel, of the ballast blocks having one edge supported on said projections and a T-shaped ballast supporting 95 key having its head working through the slots in the angle irons and its shank extended through to the inside of the vessel whereby the key may be turned and the ballast released 100 when desired, substantially as described. 105

3. In a diving apparatus, the combination with the hermetically closed vessel, the tube H passing through a packed bearing in the wall of the vessel, the jaws M pivotally supported on the outer end of the tube and the handle on the inner end of the tube; of the rod N passing through the tube and having the head and annular groove on the outer end cooperating with the jaws and the nut screwing upon the inner end of the rod substantially as described. 110

4. In a diving apparatus, the combination with the hermetically closed vessel the socket secured in the wall thereof and the ball secured in the socket and having an aperture through the same, of the tube passing through the aperture and carrying a tool at the outer end, a rod for operating the tool passing through the tube and a packing gland surrounding the tube within the ball with means for holding the ball against rotation as the gland is set up or loosened; substantially as 120 described. 125

5. In a diving apparatus, the combination with the hermetically closed vessel having 130

the packed bearing in its wall, of the tube passing through said bearing and carrying a tool upon the outer end, the handled nut screwing upon its inner end and having 5 the packing gland therein, the rod passing through the nut and tube for operating the tool, the nut on the inner end of the rod secured to the handled nut on the tube whereby the rod may be given a longitudinal movement; substantially as described.

In testimony whereof we have hereto set our

hands in the presence of the two subscribing witnesses.
